UNITED STATES PATENT OFFICE.

THOMAS P. MARGESON, OF MELROSE, MASSACHUSETTS, ASSIGNOR TO
HERBERT M. SYLVESTER, OF SAME PLACE.

OIL-VAPORIZING ATTACHMENT FOR STOVES OR FURNACES.

SPECIFICATION forming part of Letters Patent No. 592,571, dated October 26, 1897.

Application filed January 25, 1897. Serial No. 620,636. (No model.)

To all whom it may concern:

Be it known that I, THOMAS P. MARGESON, residing at Melrose, in the county of Middlesex and State of Massachusetts, have invented 5 certain new and useful Improvements in Oil-Vaporizing Attachments for Stoves or Furnaces; and I do hereby declare that the following is a full, clear, and exact description of the invention, which will enable others 10 skilled in the art to which it appertains to make and use the same.

My invention relates to apparatus for generating or producing heat in stoves, cooking-ranges, furnaces, &c., by the combustion of 15 vaporized oil, the vaporization of which is effected by the heat generated by the combustion.

The invention has for its object to provide a simple, durable, and efficient apparatus of 20 this character; and it consists in the improvements hereinafter described and claimed, said improvements being embodied in a heating apparatus or attachment comprising, first, an oil-vaporizing conduit or retort composed of an oil-receiving portion formed to 25 extend horizontally along the lower portion of the inclosing fire-box or other structure and provided at its outer end with means for connection with a source of oil-supply and an 30 oil and vapor delivering portion located above and preferably parallel with the receiving portion and provided with a nipple or nozzle which projects toward the receiving portion, and, secondly, a deflecting-plate located between 35 the receiving and delivering portions and adapted to deflect the flame from the said nipple, the office of the said deflecting-plate being to spread and distribute the flame, so that it is fully utilized in the inclosing structure and is caused to vaporize the oil and 40 superheat the oil-vapor in the delivering portion and also to conduct heat to the receiving portion for the purpose of vaporizing the oil therein.

45 Of the accompanying drawings, forming a part of this specification, Figure 1 is a sectional view showing my improved apparatus as it appears in a stove or range ready for operation. Fig. 2 is a view of the deflecting- 50 plate.

The same letters of reference indicate the same parts in both the figures.

In the drawings, *b b b* represent the sides and top, and *B* the grate, of an inclosing structure, which may be the fire-box of a 55 stove, range, or furnace and may be of any desired construction.

C and *E* represent the chief parts of the oil-vaporizing conduit or retort, which is formed to be inclosed in the said structure, the said 60 parts *C* and *E* being preferably made of lengths or sections of wrought-iron tubing. The receiving portion *C* is substantially horizontal and is arranged at or near the lower portion of the inclosing structure and is provided 65 at one end with means for connection with a source of oil-supply, said means as here shown being an ordinary cap or union *K* at the raised outer end of the portion *C*, said union being adapted for connection with 70 a supply-pipe *G*, which extends to an elevated oil-reservoir *F* and is provided with a stop-cock *g*. The delivering portion *E* is located above the receiving portion *C* and is connected with the latter by a tubular standard 75 *D*, which is a continuation or part of the retort. The delivering portion *E* is provided with downwardly-projecting vents or nipples *f f*, arranged to project jets of flame toward the receiving portion *C*, the said nipples *f f* 80 having outlet-orifices which are relatively very small and may be of the size commonly used in the nipples of guns which are exploded by percussion-caps.

A represents a substantially horizontal deflecting plate or surface, which is located between the receiving portion *C* and the delivering portion *E*, said plate being wider than the said receiving portion and practically co-extensive therewith as to length. The form 85 and arrangement of said plate are such that the flames projected from the nipples *f* are discharged unbroken on the plate and are deflected thereby and distributed through the inclosing structure, the flames being deflected 90 into substantially horizontal disks, which radiate from the point of impingement of the jets upon the plate *A*. The deflected flames are not only distributed through the inclosing structure, so as to cause a thorough utili- 95 100

zation of the thermal efficiency of the fuel employed, but are also arranged to subject the delivering portion of the retort to a high degree of heat, thus causing originally the 5 vaporization of the oil in said delivering portion and subsequently the superheating of the oil-vapor therein.

The deflecting-plate A becomes highly heated by the jets of flame, and as said plate 10 is in close proximity to the receiving portion C of the retort it follows that the oil in said receiving portion becomes vaporized, the oil-vapor finding its way through the tubular standard D into the delivering portion, from 15 which it escapes through the nipples f.

The operation of the device is as follows: The stop-cock g being opened to permit oil to 20 flow from the tank F into the various parts of the retort, minute streams of oil escape through the nipples f and may be ignited either directly upon the plate A or upon paper or other combustible material which may be interposed between the plate A and the nipples. Heat is immediately generated and 25 first vaporizes the oil in the delivering portion E, the vaporized oil being forced by its expansion through the nipples f and thereafter constituting the combustible agent. The deflecting-plate A becomes rapidly heated and 30 the heat conducted through it acts on the receiving portion C of the retort, vaporizing the oil therein, so that thereafter nothing but vapor enters the delivering portion E, said vapor being continuously superheated by 35 the heat from the flames deflected by the plate A.

It will be seen that the receiving portion C and the delivering portion E of the retort are exposed to the heat resulting from the combustion. Hence their walls furnish large 40 areas of oil-vaporizing and superheating surface, so that the production of combustible vapor is continuous and is sufficient in volume without the necessity of employing an enlarged storage-reservoir for the gas and vapor. Hence I am enabled to make the entire 45 oil containing and vaporizing apparatus from lengths or sections of wrought pipe or tubing of comparatively small diameter, so that the construction is very simple and inexpensive. 50 The plate A, located between the receiving and delivering portions of the retort and arranged to distribute the flame so as to insure the maximum thermal efficiency of the combustion within the inclosing structure, also 55 insures the heating of both parts of the retort, the receiving portion being heated by conduction through the plate and the delivering portion by upward radiation.

Owing to the above-described arrangement 60 for effectively heating all parts of the retort, I find that there is no liability of obstruction

of the retort or the nipples f by accumulations of sediment in the retort, all foreign matter contained in the oil being apparently consumed by the high degree of heat to which 65 all parts within the inclosing structure are subjected.

The device can be easily adapted for immediate use in any heat-producing apparatus in which wood or coal is used. It can be introduced into any cooking stove or range when 70 constructed as shown in the drawings, and the same device may be as readily used in a furnace by changing the plate A from an oblong to a circular form, the receiving and delivering parts being correspondingly formed. 75

As here shown, the outer end of the receiving portion C is closed by a cap i and the ends of the delivering portion E by caps e e, the standard D being connected with the receiving and delivering portions by T-joints c and h. I do not limit myself to this construction, however, as the same may be variously modified without departing from the spirit of my 80 invention. 85

The plate A is or may be supported by legs or yokes a a, formed to rest on the grate B.

I prefer to make the plate A removable from the retort, so that it can be removed and a new one substituted, if desired. The plate is 90 preferably of hardened steel to make it suitably refractory. It will be seen that by using a refractory plate in close proximity to the receiving portion of the retort, which plate is directly acted on by the jets of flame and distributes said jets so that they radiate heat upon the delivering portion of the retort, I insure the efficient heating of all portions without direct impingement of the flame upon any portion of the retort, thus preventing liability of burning out the retort, the plate A 95 being readily removable if injured by the direct impingement of the flames upon it. 100

I claim—

In an apparatus of the character specified, 105 the combination of a receiving retort portion, a delivery retort portion located above said receiving portion and provided with a jet-orifice adapted to discharge toward the latter, and a protector and deflector situated between 110 the two portions and contiguous to the receiving portion, the distance between the jet-orifice and the protector and deflector being such that the jet of vapor will discharge unbroken upon the latter, substantially as set forth. 115

In testimony that I claim the foregoing as my own I have affixed my signature in the presence of two witnesses.

THOMAS P. MARGESON.
